CLAIM

The ornamental design for a jug, as shown and described.

DESCRIPTION

FIG. 1 is a top, rear, left perspective view of a jug, showing my new design;

FIG. 2 is a rear view thereof;

FIG. 3 is a front view thereof;

FIG. 4 is a right side view thereof;

FIG. 5 is a left side view thereof;

FIG. 6 is a top view thereof; and,

FIG. 7 is a bottom view thereof.

The broken lines and the area within the broken lines, shown in FIGS. 1 and 6–7, depict portions of the jug which form no part of the claimed design.

1 Claim, 7 Drawing Sheets(56)
